FISHING SINKER

Samuel Candella, Buffalo, N. Y.

Application July 7, 1955, Serial No. 36,861

Term of patent 7 years

(Cl. D31—4)

Fig. 1.

Fig. 2.

Fig. 1 is a top plan view of a fishing sinker showing my new design, and

Fig. 2 is a side elevational view thereof.

I claim:

The ornamental design for a fishing sinker, substantially as shown.
